UNITED STATES PATENT OFFICE.

CLARENCE L. HEALY, OF BROOKLYN, ASSIGNOR TO THE COMMERCIAL TELEGRAM COMPANY, OF NEW YORK, N. Y.

PRINTING-TELEGRAPH.

SPECIFICATION forming part of Letters Patent No 341,656, dated May 11, 1886.

Application filed February 9, 1886. Serial No. 191,280. (No model.)

To all whom it may concern:

Be it known that I, CLARENCE L. HEALY, of Brooklyn, in the county of Kings and State of New York, have invented a certain new and 5 useful Improvement in Printing-Telegraphs, of which the following is a specification.

Heretofore in printing-telegraphs wherein the receivers or printers are provided in the circuit of the type-wheel escapement-magnets 10 with a neutral magnet caused by variations in the strength of current in such circuit to attract its armature or permit it to fall away, and thus effect the shifting of the movement from one type-wheel to the other, it has been 15 usual to produce this variation in the current by throwing resistance into the circuit after the type-wheel is positioned, but before the printing-magnet acts. By my present invention I accomplish the same end in a simpler, 20 and, under some circumstances, more desirable way, by shunting or grounding the line.

The invention is illustrated in the accompanying drawing, which is a view principally in diagram of the apparatus.

25 A is the transmitter key-board, having letter and figure keys *a* and unison-keys *b b'*. These keys *b b'* act upon a switch-lever, *c*, pivoted between them, and shifted one way or the other by the depression of such keys. At 30 its outer end switch-lever *c* plays over two blocks, *d d'*, resting on one or the other, according to whether key *b* or *b'* were last depressed. Wires 1 2 run to blocks *d d'*, and through lever *c* form the base-connection of key-board A.

35 B is the "sunflower" of transmitter, C the current-reversing drum, and D the stopping-magnet. The blocks of sunflower are connected by wires 3 to contact-springs *e* beneath the keys of transmitter, while the arm *f*, traveling 40 over sunflower, is connected by wire 4 to stopping-magnet D, and from thence to one pole of a battery, E, dynamo-electric machine, or other source of electrical energy. Wire 1 runs to one side of a relay magnet, F, to the 45 other side of which is a connection, 5, from battery E. Magnet F controls, directly or indirectly, the local circuit including the printing-circuit relays, as will be well understood. Wire 2 runs to another magnet, G, and from 50 thence to wire 1. Magnet G is the shifting-

magnet for varying the current in the type-wheel circuits at the printers.

It will be seen that the operating-circuit of transmitter includes wire 1 or wire 2, according to position of switch-lever *c*. When lever 55 *c* is on block *d*, wire 1 is in circuit, and so is magnet F, magnet G being out of circuit. When lever *c* is on block *d'*, wire 2 is in circuit, and so are both magnets F and G.

L is one of the type-wheel line-wires, including at each printer on the line the type-wheel escapement-magnets H and the neutral magnet I. This line runs to a central brush, *g*, on transmitter-cylinder B, and is connected by plates on cylinder alternately with two 65 other brushes, *h h'*, connected by wires 6 7, through oppositely-arranged batteries K K', to earth.

As so far described in connection with the drawing, the apparatus is that well understood 70 and at present in use.

Heretofore magnet G has been employed to throw resistance into line L, causing neutral magnet I to release its armature. By this invention an earth-connection, 8, is made from 75 line L at a point between transmitter-cylinder B and the first printer on the line, which earth-connection is controlled, directly or indirectly, by magnet G. As shown, the earth-connection 8 runs to armature lever of magnet G, and to 80 the front point thereof. A resistance, R, is preferably included in this ground-connection, and this resistance is preferably adjustable, as shown, so as to permit of an adjustment of the ground-connection to the conditions of the 85 line, and to compensate for any change that may be made in the number of printers on the line, although the connection 8 may run directly to earth. With switch-lever *c* on block d, as shown, when the transmitter is stopped 90 the full current will remain on line L, magnet G not being energized, and neutral magnets I of printers will attract their armatures, and the printing will be effected (through circuits controlled by magnet F) with full current on 95 type-wheel lines and armatures of magnets I drawn forward. With switch-lever *c* on block *d'*, bringing magnet G into operating-circuit, when transmitter is stopped magnet G will close ground-connection 8, and the current 100

from line L will be shunted from the printers to earth. The neutral magnets I of printers will thus be weakened or demagnetized, and will permit their armatures to fall back, and 5 the printing will be effected with armatures of I in this retracted position.

What I claim is—

1. In printing-telegraphs, the combination, with a transmitter and printers operated 10 therefrom, of the type-wheel line including the escapement-magnets and neutral shifting-magnets and a ground-connection from type-wheel line between transmitter and printers, said ground-connection being controlled by 15 the transmitter for shunting current from the type-wheel line when the transmitter is stopped, substantially as and for the purpose set forth.
2. In printing-telegraphs, the combination, 20 with a transmitter and printers operated therefrom, of the type-wheel line including the escapement-magnets and neutral shifting-magnets, a ground-connection from type-wheel line between transmitter and printers, a magnet controlling said ground-connection, and means at the transmitter for controlling this 25 magnet, substantially as and for the purpose set forth.
3. In printing-telegraphs, the combination,

with a transmitter and printers operated 30 therefrom, of the type-wheel line including the escapement-magnets and neutral shifting-magnets, a ground-connection from type-wheel line between transmitter and printers, a magnet controlling said ground-connection, and a 35 switch at the transmitter key-board for including this magnet in the transmitter-operating circuit, substantially as and for the purpose set forth.

4. In printing-telegraphs, the combination, 40 with a transmitter and printers operated therefrom, of the type-wheel line including the escapement-magnets and neutral shifting-magnets, a ground-connection from type-wheel line between transmitter and printers, said 45 ground-connection being controlled by the transmitter for shunting current from the type-wheel line when the transmitter is stopped, and an adjustable resistance in said ground-connection, substantially as and for the purpose set forth.

This specification signed and witnessed this 23d day of January, 1886.

CLARENCE L. HEALY.
